UNITED STATES PATENT OFFICE.

JOHN SUMNER BOOTH, OF DALLAS, TEXAS.

HAT TRAY.

Application filed October 15, 1921. Serial No. 507,863.

To all whom it may concern:

Be it known that I, JOHN SUMNER BOOTH, a citizen of the United States, and a resident of Dallas, in the county of Dallas and State of Texas, have invented certain new and useful Improvements in Hat Trays, of which the following is a specification.

The present invention relates to an improvement in hat trays, particularly adapted for use with straw hats.

The object of the invention is to provide a hat tray of this character which safely packs or crates a relatively large number of hats in a compact space, which is especially adapted for use in the packing of hats in trunks as is the practice among salesmen, jobbers and others, which is adjustable so as to be capable of use with various styles and sizes of hats, and which is in general of simple and durable construction, convenient in use and easy and inexpensive to manufacture.

Other objects and advantages of the invention reside in certain novel features of construction, combination and arrangement of parts which will be hereinafter more fully described and particularly pointed out in the appended claims, reference being had to the accompanying drawings forming part of this specification, and in which:

Figure 1 is a perspective view, showing the crate stood on end;

Figure 2 is a view in vertical section of the tray in the position shown in Figure 1;

Figure 3 is a plan view, illustrating the first step in packing the hats;

Figure 4 is a similar view, illustrating the second step;

Figure 5 is a similar view, illustrating the third and final step;

Figure 6 is a perspective view illustrating another embodiment of the invention;

Figure 7 is a detail view of the sectional or demountable post; and

Figure 8 is a detail view in section of a modified form of base.

Referring to the drawings wherein for the sake of illustration is shown the preferred embodiment of the invention the numeral 10 designates generally the base of the tray which comprises side bars 11 and end bars 12 which extend across and are secured to the side bars. Cross slats 13 extend between and are secured to the side bars of the base and have strips 14 of cushioning material such as felt or the like, secured to

their upper surface. These cross slats 13 constitute the floor of the crate and receive the lower tier of straw hats, as will be hereinafter more fully described.

60.

If desired the strips of felt 14 provided on the cross slats may be omitted and a covering of cloth or similar material may be provided on the base, as indicated in Figure 8. It is obvious that if desired the floor may be 65 made solid and provided with suitable cushioning means such as a surfacing of felt or the like. Posts 17 upstand from the corners of the base and rest upon the end bars 12 thereof. These posts 17 comprise a long leg 70 18 and a short leg 19 and may consist of one solid piece, as shown in Figures 1 and 2 or may consist of a sectional construction, as shown in Figure 7. In the sectional construction, as shown in Figure 7, the legs are 75 designated at 21 and 22, and are releasably secured to each other by means of screws and bolts 23 and 24 or other releasable fastening means. Preferably the sectional posts are employed since they provide a 80 means whereby the trays may be adapted for use with hats of different height crowns as the posts 21 are provided in various lengths. Thus the tray may be adapted from season to season to the various styles of hats in 85 vogue, since the height of the crown of the hat is usually one of the features thereof which is changed in accordance with the changing styles.

A frame, designated generally at 25 is arranged on the base and includes longitudinal side bars 26 overlying and extending longitudinally of the base and secured at their ends to the short legs of the posts 17 and supported intermediate their ends by means 90 of supporting blocks 27 which rest upon the side bars 11 of the base. Adjacent the ends of the side bars 26 cross bars 28 are provided and extend between and are secured to the side bars. The side bars 26 and the 95 cross bars 28 are provided on their inner surfaces with strips of felt, designated at 29 and 30 respectively, the strips of felt constituting cushioning means for the hats. End bars 31 are superposed on the longitudinal bars at the ends thereof, and the ends of the end bars are secured to the post 17 whereby these end bars not only enter into the construction of the frame 25 but also 100 brace and strengthen the posts 17.

105

In packing the hats in the crate they are arranged in tiers, as illustrated in Figures

110

3, 4 and 5. The hats of the first tier, which are designated at H, are six in number and are arranged as shown in Figure 3 with their brims resting on the cushioning cross slats 5 of the base. The hats of the second tier are arranged at H' and are arranged in the spaces between the hats of the first tier with their brims resting on the brims of the hats of the first tier, and are two in number, 10 as shown in Figure 4. The hats of the third tier are designated at H², are seven in number, and are arranged inverted or upside down with their crowns received in the spaces between the hats of the underlying 15 tiers and with their brims arranged in substantially the same plane as indicated in Figure 5.

Means is provided for securing the tiers of hats against displacement in the tray and 20 preferably consists of elastic bands 33 adjustably secured, as at 34, to the longitudinal bars 26 of the frame 25 and elastically bearing on the inverted brims of the hats of the upper tiers.

25 It is obvious that if it should be found desirable to pack somewhat less than fifteen hats in the tray, dummies may be provided for the hats and may consist simply of an open ended ring or cylinder corresponding 30 to the size of a hat and inserted in the tray in place thereof.

The embodiment of the invention shown in Figure 6 is usually to be preferred and is identical in all respects with the embodiment 35 above described, except that one of the cross bars of the frame is made adjustable. In this embodiment the base is designated at 35 and the frame at 36. The adjustable cross bar of the frame is shown at 37 and has 40 its ends provided with metallic caps 38 which are provided with bearing portions 39 which are rounded to engage the inner surface of the longitudinal side bars of the frame 36 and which serve to connect the adjustable cross bar to slides 40 which embrace 45 the longitudinal side bars 36^a of the frame and which are connected to adjusting straps 41 secured to the outer sides of these side bars 36 and embodying buckles 42 for securing 50 the straps and consequently the adjustable cross bar in any position. It is obvious that the adjustable cross bar 37 may be moved longitudinally of the frame in order to adapt the frame to hats of various sizes.

55 These trays packed with hats as shown in Figure 5 are adapted to be arranged one on top of the other in a trunk or similar receptacle and when so used it is convenient and practicable to pack one hundred and 60 twenty hats in the same trunk in which no more than fifty-six could be packed by using any of the trays heretofore known in the art. Manifestly this is a great saving to a traveling man, jobber or factory with respect to excess baggage and wear and tear 65

on trunks and makes it possible to transport the same number of hats with one-half the number of trunks.

In Figure 8 a modified form of the invention is shown wherein the base is constructed of a solid piece as shown at 50 and is provided with a covering of fabric designated at 51. This fabric may be of any textile material and if desired have cushioning properties, as for instance, it consists of felt or the like. This form of the invention is identical in all other respects with the embodiment shown in Figures 1 to 5, although if desired, it may include the adjustable cross bar shown in Figure 6. 80

I claim:

1. In a hat tray, a base including side bars and end bars and a plurality of spaced cross slats provided with strips of felt and constituting a floor for said base, posts upstanding from the corners of said base and including a short leg and a long leg detachably secured to said short leg, a frame mounted on said base and including longitudinal bars secured at their ends to said post, supporting blocks arranged on said base and supporting said longitudinal bars intermediate their ends, cross bars extending between said longitudinal bars adjacent their ends, said longitudinal bars and said cross bars being provided with strips of felt constituting cushioning means for the hat, said frame being adapted to receive said hats piled therein tier on tier, end cross bars superposed on said longitudinal bars 100 and secured to said post, and means for securing said tiers of hats in position in said tray including elastic clamping bands releasably secured to the longitudinal side bars of the frame and elastically bearing on 105 the hats of the uppermost tier.

2. In a hat tray, a base including a floor provided with cushioning means for the hats, posts upstanding from the corners of said base and including a pair of lugs releasably secured to each other, a frame arranged on said base and provided with cushioning means for the hats, the base and frame being adapted to receive the hats piled tier on tier therein and elastic clamping bands releasably secured to the frame and elastically bearing on the uppermost tier of hats for retaining the hats in position in said frame. 110

3. In a hat tray, a base, posts upstanding from the corner of said base, and a frame mounted on said base and including a movable cross bar, and means for adjusting and securing said movable cross bar in adjusted position. 120

4. In a hat tray, a base, and a frame on said base having a movable cross bar, caps on the ends of said cross bar provided with rounded bearings slidably engaging the frame, slides connected with the bearings 130

of said cap and slidably embracing the frame, straps coacting with said slides, and buckles coacting with said straps.

5. In a hat tray, a base including a floor for the hats, posts arranged on said base and a frame mounted on the base and including longitudinal bars secured to said posts, supporting blocks arranged on the base and supporting the longitudinal bars of the frame, and cross bars arranged adjacent the end bars of said frame, one of said cross bars being adjustable.

6. In a hat tray, a base including a floor for the hats, posts arranged on said base and a frame mounted on the base and including longitudinal bars secured to said

posts, supporting blocks arranged on the base and supporting the longitudinal bars of the frame, and cross bars arranged adjacent the ends of the longitudinal bars of 20 said frame.

7. In a hat tray, a base including a floor for the hats, sectional posts arranged on said base and including a pair of legs releasably secured to each other and a frame 25 mounted on said base and including an adjustable cross bar.

8. In a hat tray, a base, a frame arranged on said base and adapted to receive the hats piled tier on tier therein, and means for 30 retaining the hats in position in said frame.

JOHN SUMNER BOOTH.
